UNITED STATES PATENT OFFICE.

WILLIAM A. SORG, OF MINNEAPOLIS, MINNESOTA, ASSIGNOR, BY MESNE ASSIGNMENTS, TO FREDERICK G. BRADBURY, TRUSTEE, OF ST. PAUL, MINNESOTA.

COMBUSTION-ENGINE.

1,209,061.

Specification of Letters Patent. Patented Dec. 19, 1916.

Application filed March 2, 1914. Serial No. 821,909.

To all whom it may concern:

Be it known that I, WILLIAM A. SORG, a citizen of the United States, residing at Minneapolis, in the county of Hennepin and 5 State of Minnesota, have invented a new and useful Improvement in Combustion-Engines, of which the following is a specification.

An object of this invention is to provide an internal combustion engine in which 10 heavy and light fuel oils are completely vaporized in the combustion chamber in the most effective manner.

More particularly in the present invention a long tubular combustion chamber associated with an outside cylinder is employed which is heated through the action of the combustion of fuel to produce thorough vaporization of heavy fuel oils such as kerosene and crude petroleum, and said outside 20 cylinder is detachably mounted upon a tube which is adapted to be heated and to hold the fuel mixture charge.

The invention further consists of combining a cool cylinder and a heated tube in 25 which the fuel oil is directly vaporized, said tube being chilled and rid of incandescent particles to prevent pre-ignition.

This invention makes it practicable to burn kerosene and crude oil having acid reaction 30 or containing sulfur, because the fuel is sprayed and retained in a tube adjacent the cylinder and does not come into contact with the cylinder wall.

One of the important results of this invention is to prevent combustion and "after burning" of the fuel following the working stroke.

This application is directed to a portion of the subject matter forming a separate 40 specie of the invention involved in my companion applications, Serial Numbers 821,908 and 821,911, filed on the 2nd day of March, 1914, for improvements in combustion engines.

45 In the accompanying drawings forming part of this specification, Figure 1 is a plan of my invention; Fig. 2 is an end view, part of the engine being broken away and in section for the purpose of exposing part of the 50 internal construction, and Fig. 3 is an enlarged detail in section taken longitudinally through the central portion of the engine.

In the drawings. A indicates a reciprocable insitile piston, B a stationary outside 55 cylinder in which the piston reciprocates and

D a long tubular structure having a bore of less diameter than the diameter of said piston and forming a combustion chamber in extension of the cylinder in which the charge of fuel is adapted to be formed and entirely 60 consumed. The piston A is provided with the usual pitman 2 which revolves a crank shaft 3 in the usual manner, said shaft being journaled in bearings 4 mounted upon the base 5, said base being adapted to support the cylinder B in stationary position. The cylinder B is formed with a jacket 6, the chamber of which has ports 7 which provide for a circulation of cooling medium such as water through the jacket. In this 70 manner, a cool, cylindrical bearing surface is provided on which the piston is adapted to reciprocate. The piston A is provided with the usual piston rings 8 seated in annular grooves 9 whereby a tight working 75 connection is produced between the piston and cylinder to enable the forming of a charge of fuel in the combustion chamber under sufficient compression to produce highly efficient results. The combustion 80 chamber tube D is flared on one end and its rim 10 detachably secured to an end of the cylinder such as by bolts 11, the tube cylinder and piston being disposed co-axially.

The free or outer end of the tube D is 85 shown provided with a fuel manifold 12 connecting with a suitable source of fuel mixture supply such as the carbureter 13, although it is not necessary to employ a carbureter because the tube acts as an efficient 90 mixer for air and fuel. This manifold has a puppet valve 14 seated on its inner end and disposed with its stem on the axis of the tube. This valve is held closed upon its seat by the spring 15, said spring permitting 95 the valve to open during the suction stroke of the piston to draw in a charge of fuel mixture issuing from the carbureter. Immediately adjoining the fuel valve is an exhaust valve 16, the latter being disposed 100 upon a seat in the side of the tube and adapted to be opened at even periods to exhaust the spent gases during the scavenging or exhaust strokes of the piston. This valve is closed automatically at the end of the exhaust stroke by means of the spring 17 on the outer end of the stem 18 of said valve. The stem 18 is slidably mounted in the casing 19 having the outlet 20 for the exhaust, 105 said casing being jacketed for cooling pur- 110

poses. The jacket chamber 21 is provided with port passages 22 and 23 to provide for a circulation of cooling medium such as water through the jacket, the port passage 22 being connected to the port passage 7 in the cylinder jacket by means of the tube 24 whereby the water used for cooling purposes is adapted to pass through the chambers in the jacketed cylinder and exhaust valve casting in series. Disposed in the side of the free end of the tube D immediately opposite the exhaust valve is an air inlet valve 25, which is seated in a valve cage 26, the latter being secured in a suitable casing 27 formed on the side of the tube such as by means of bolts 28. The valve 25, which is seated in the cage 26, is provided with the usual stem 28' and is adapted to be closed automatically by means of the spring 29 on the outer end of the stem. Air is admitted into the cage by the port passages 30 and when the valve 25 opens passes into the outer end of the tube or combustion chamber. A suitable igniter such as the electric spark plug 31 is seated in the side of the combustion chamber in advance of the fuel valve 14 and is adapted to ignite the fuel in the combustion chamber at the usual time.

The valves 14, 16 and 25 are opened and closed in synchronism with the strokes of the piston to effect the forming of a stratum of fuel adjacent the free end of the tube, a stratum of inert gas adjacent the head end of the piston and a stratum of air between the stratum of fuel and the stratum of inert gas during the suction stroke of the piston. The valve 25 is positively opened by the use of a walking beam 32 mounted upon the valve cage 26, and is connected with a trip lever 33 which is pivoted upon a boss 34 on the side of the tube by means of the connecting rod 35. The trip lever 33 is moved to open the valve during the early portion of the suction stroke of the piston by means of a cam 36 mounted upon a shaft 37, which is journaled upon the bed of the machine and revolved by the crank shaft 3 through the use of intermeshing spiral gears 38 and 39. As the strength of the spring 29 on the air valve is greater than the strength of the spring 15 on the fuel valve 14, the valve 14 remains closed during a portion of the suction stroke and does not open until the valve 25 has closed. Immediately upon the valve 25 closing after a stratum of air has been admitted into the tube, the valve 14 opens automatically and admits fuel and air which mix and form in another stratum. At the end of the suction stroke both valves 14 and 25 close. As a result, the inert gas, air and fuel mixture are formed in separate strata and compressed while they remain in strata formation in the tube during the compression stroke. In this condition the fuel is in most advantageous condition to pro-

duce efficient results when the stratum of fuel mixture is ignited. The tube is of sufficiently small diameter and of sufficient length to hold the entire charge of fuel mixture. During the formation and compression of the stratum of fuel in the tube it is impinged against the hot inner surface of the tube, and its temperature raised. In consequence a thorough mixing action takes place and the heavy particles of oil are rendered volatile and in prime condition to produce substantially complete combustion with little or no waste.

During the operation of the engine there is a tendency of some of the impurities or residue from the products of combustion in the tube to collect and form a deposit around the piston rings in the concentric channels 9, and cause the rings to stick and not work freely thus decreasing the compression of the fuel produced by the piston. For the purpose of reducing this tendency and increasing the efficiency of the operation of the engine by forming a perfectly tight joint between the piston and cylinder wall and also to cool the surface of the piston and inner wall of the cylinder, water or suitable liquid in small quantities is sucked up into the cylinder through the port passage 42. This port passage is so positioned that it is uncovered immediately before the end of the suction stroke of the piston whereby the liquid is sucked up between the piston and cylinder and over the head of the piston. The hot gases in the combustion chamber and the hot piston head vaporize the liquid and the vapor thus formed prevents the burning and decomposition of the impurities or oil which tend to collect around the piston rings. The liquid which is admitted through the port passage 42 may be a mixture of air and water or any other liquid or mixture of ingredients which may be capable of spreading in contact over the surface of the piston and piston rings to prevent the carbonization of the ingredients which come into contact with the piston rings and cause them to stick. The water or other material which is admitted through the port 42 instead of being sucked into the cylinder or in contact with the wall of the piston may be forced under pressure through the port passage other than through the suction produced by the piston when desired. It is intended that the feature of admitting water through the port 42 into the cylinder shall not form a special feature of this invention, it being intended that the engine shall be used without its use.

We are now in a position to form the following picture of the processes which follow upon the ignition of the combustible gas mixture contained in the long tube after the strata of fuel, air and vapor or steam have been compressed. First there is the

condition of slow combustion; the heat being conveyed by conduction to the adjacent layers, and there therefore follows a slow velocity of flame propagation.

5. Immediately after the working stroke of the piston the exhaust valve 16 is opened through the action of a walking beam 40 which is pivoted upon the bed of the machine. This beam depresses the valve 16 inwardly against the force exerted by the spring 17. The walking beam is tilted at the proper instant and for the proper period of time to hold the exhaust valve open during the scavenging stroke of the piston by 10 the cam 41 mounted upon the shaft 37.

15. In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above 20 set forth within the scope of the following claims.

25. Having described my invention, what I claim as new and desire to protect by Letters Patent is:—

30. 1. A combustion engine, comprising, in combination, an inside piston and an outside cylinder in reciprocable connection, a long tube detachably mounted on one end of said cylinder forming a long combustion 35 chamber of less diameter than the diameter of said piston, the free end of said tube being valved to admit of the forming of a stratum of fuel in said tube and a stratum of air in the chamber formed by said tube, 40 cylinder and piston and to exhaust spent gases and means for igniting the charge of fuel in said tube.

45. 2. A combustion engine, comprising, in combination, a reciprocable inside piston and an outside cylinder in which said piston is slidably mounted, said cylinder having a jacket forming a chamber through which a cooling medium is adapted to be circulated, a long tube forming a combustion chamber 50 detachably mounted on an end of said cylinder having a bore of less diameter than the diameter of said piston and adapted to be heated to assist in vaporizing fuel mixture therein, means on the free end of said 55 tube for admitting fuel into said tube, means for exhausting spent gases from the

free end of said tube, means for admitting air into the free end of said tube, said fuel and air being arranged in separate strata in said tube, and means for igniting the fuel in the tube.

3. A combustion engine, comprising, in combination, an inside piston, a stationary element comprising a long tube adapted to be heated and to form a hot combustion chamber to assist in vaporizing the fuel and a bearing element in the form of an outside cylinder on an end of said tube, in which said piston is slidably mounted, means for lubricating the adjacent surfaces between said bearing element and piston, means for admitting a fuel charge into the free end of said tube, means for admitting air into the free end of said tube in advance of the admission of fuel and in a separate stratum from the fuel to chill the inner surface of the tube, wash out incandescent particles and prevent pre-ignition of the fuel charge, means for exhausting spent gases from the tube and means for igniting the fuel in the tube whereby the fuel is retained in a long column and consumed and a prolonged force is exerted against the piston during its working stroke.

4. A combustion engine, comprising, in combination, a piston and cylinder in reciprocable connection, said cylinder consisting of a cylindrical portion in which said piston is adapted to be reciprocated and chambered to circulate a cooling medium therethrough and a long tube extending from one end of said cylinder having a bore of materially less diameter than the diameter of said piston and adapted to be heated to a high temperature by the consumption of fuel therein to assist in directly vaporizing fuel oil therein, said tube having in its outer end-valved ports, through which air and fuel oil are formed in separate strata in said tube and spent gases are exhausted, 100 said air being adapted to chill the inner surface of the tube, wash out incandescent particles and prevent pre-ignition, and means for igniting the stratum of the fuel in said tube.

105. In testimony whereof, I have signed my name to this specification, in the presence of two subscribing witnesses.

WILLIAM A. SORG.
